SORTING MACHINE

Jack J. Constance, Bartlesville, Okla., assignor to
 International Business Machines Corporation,
 New York, N. Y., a corporation of New York

Application June 17, 1948, Serial No. 33,585

1 Claim. (Cl. 209—110)

1

The present invention relates to sorting machines and more particularly to sorting machines in which perforated record cards are fed singly from a magazine and distributed to selected pockets in accordance with the location of perforations in the card columns.

The principal object of the invention is to provide checking devices for checking the sequence of a series of record cards according to data perforations in one column thereof, while the cards are being sorted in accordance with data perforations in another column thereof.

A further object of the invention is to provide improved devices for checking the occurrence of erroneous data perforations in a card column during sorting operations.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a view, partially in section, of the card feeding and distributing mechanism of a well known type of sorting machine.

Fig. 2 is a view looking in the direction of lines 2—2 of Fig. 1.

Figs. 3 and 3a placed one above the other constitute a wiring diagram of the machine.

Fig. 4 is a timing diagram of certain of the electrical devices.

The general method of procedure in operating a record card sorting machine to arrange a stack of cards in numerical order will first be briefly explained, after which the manner in which the present invention is carried out will be set forth in detail.

Briefly, the sorter includes a supply magazine 10 (Fig. 1), a card picker 11 for feeding the cards one at a time through a throat 12, and means comprising a linkage 13 operating from a main shaft 14 for actuating the picker. As a record card passes through the throat, it is gripped between a set of rollers 15 and fed to an analyzing device consisting of the usual metallic roller 16 and analyzing brushes 17S and 17C (Fig. 2) which are spaced apart the distance between adjacent card columns. The usual sorter is provided with only a single brush 17S and for the purpose of the present invention the second brush 17C is provided.

These brushes are insulated from one another and mounted in a holder 18 which is threaded on a screw 19. The pitch of screw 19 is such

that one revolution of a handle 20 at its end will shift brushes 17S, 17C one column space in either direction. As usual, the screw is mounted for vertical reciprocation and carries cams 21 at its extremities which cooperate with stationary rollers 22, so that at the beginning of the rotation of screw 19 it will be cammed upwardly to lift the brushes off contact roller 16, and near the end of the revolution of the shaft the brushes 10 will descend again. For the purpose of the present invention, a pair of contacts 23 (Fig. 1) are provided and arranged with the upper blade thereof extending over the hub of handle 20. Thus, whenever the brushes are shifted, the incidental lifting of screw 19 will cause opening of contacts 23.

As the card continues to pass beneath the brushes, its forward edge moves beneath the upturned edges 24 of a plurality of guide blades 25 which lead to the various sorting pockets.

Immediately upon the analyzing brush 17S encountering a perforation in the record card column with which it is aligned, a magnet 26 is energized attracting its armature 27. If, when armature 27 drops, the card has passed under some of the blades, the card will continue to hold these blades in their upper position. The other blades will drop with the armature 27 and the card will then move in the path formed by the first of the lowered blades which will guide the card to the pocket corresponding to the position of the hole in the card.

Located in the path of the cards are the so-called card levers 28 and 29 which are actuated by the passing cards to close contacts CL1, CL2 and CL2a as diagrammatically represented in Fig. 3a.

The usual distributing commutator generally designated 30 (Fig. 3a) is suitably geared to main shaft 14 to make one revolution for each card cycle and the relative timing of its related wipers D1, D2 and D3 is as shown in the time chart (Fig. 4), wherein are also shown the times in the cycle when the hole positions in the cards are at brushes 17S and 17C. It will be noted that during the first cycle of operation card lever contacts CL1 close near the end thereof and in the next cycle contacts CL2 and CL2a close near the middle of the cycle. These levers are constructed as usual so that, when closed, they remain so as long as cards continue to follow in succession, since the leading card does not leave the lever until the following card has engaged it.

For the purposes of present invention, a pair

3

of timing contactors designated **T1** and **T2** (Fig. 3) are provided and each comprises a ring of stationary contact segments **31** and wipers **32**, which latter are geared to main shaft **14** so that they contact segments **31** at times in the cycles indicated in Fig. 4.

The operation of the machine may best be explained by assuming a particular example and following through the sequence of operations with respect thereto. Let us assume that a group of cards each containing a three-position number in, say, columns **50**, **51** and **52** are placed in the card magazine **10** with the numbers arranged in random order as, for example:

Card Columns.....	50	51	52	53
	2	8	9	
	4	6	5	
	5	2	3	
	3	2	0	
	6	5	7	
	0	6	9	
	3	4	2	
	2	5	4	
	8	3	6	
	1	2	8	
	9	1	8	
	2	7	0	
	1	0	4	
	5	5	5	
	7	6	0	
	8	9	5	
	4	9	5	
Brushes.....			178	17C

The sorting brush **17S** is adjusted to traverse the units order column **52** (with brush **17C** traversing a blank column **53**), and the cards are fed through the machine resulting in their distribution into the several pockets in the following order:

Pocket.....	9	8	7	6	5	4	3	2	1	0
					465					
					555					
					289					320
					895					270
					254					760
					657					
					523					
					342					
					495					
					104					
					918					
					836					
					069					

The operator now removes the cards from the several pockets and replaces them in the magazine **10** in ascending order of their units values as follows:

Card Columns.....	50	51	52
	2	8	9
	0	6	9
	1	2	8
	9	1	8
	6	5	7
	8	3	6
	4	6	5
	5	5	5
	8	9	5
	4	9	5
	2	5	5
	1	0	4
	5	2	3
	3	4	2
	2	7	0
	7	6	0
Brushes.....		17S	17C

Sorting brush **17S** is shifted to traverse the tens column **51** and brush **17C** will traverse units column **52**. The cards are now resorted according to the tens order digits, and during this sort brush **17C** will through circuits to be explained ascertain whether the units or digits follow in ascending sequence and, if a card is out of sequence, the machine will stop. Such possible misarrangement may be due to carelessness on

4

the part of the operator in removing the cards from the pockets and replacing them in the magazine.

Assuming the cards are in correct order, the second sort will result in the following distribution.

Pocket	9	8	7	6	5	4	3	2	1	0
				069	657				128	
				465	555				523	
				289	270	760	254	342	836	320

The operator now again removes the cards from the several pockets and replaces them in the magazine **10** in ascending order of their tens values as follows:

Card Columns.....	50	51	52
	8	9	5
	4	9	5
	2	8	9
	2	7	0
	0	6	9
	4	6	5
	7	6	0
	6	5	5
	3	4	2
	2	3	0
	1	2	8
	5	2	3
	3	4	2
	2	7	0
	7	6	0
Brushes.....	17S	17C	

Sorting brush **17S** is shifted to traverse the hundreds column **50** and brush **17C** will traverse tens column **51**. The cards are resorted according to the hundreds order as follows:

Pocket.....	9	8	7	6	5	4	3	2	1	0
					895					289
					555					270
					523					760

Upon removal from the pockets and arranged in ascending sequence, the cards are now in proper numerical sequence as follows: 918, 895, 836, 760, 657, 555, 523, 495, 465, 342, 320, 289, 270, 254, 128, 104, 069.

If desired as a final check, the cards may be placed in the magazine, brush **17S** shifted to traverse a blank column **49** with brush **17C** traversing the hundreds column **50**. As a result, all the cards will feed into the "reject" pocket while brush **17C** checks for correctness of sequence.

Circuit diagram

Referring now to the circuit diagram, the several circuits will be explained to point out the manner in which sorting and checking are carried out. As a preliminary, current is supplied to the + and - sides of line (Fig. 3a) and with the initial set of cards in magazine **10** and brush **17S** in line with the units column **52**, start key contacts **33** are closed manually to complete a circuit from the + side of line, through contacts **33**, relay **R30**, relays **R31** and **R32** in parallel to - side of line. Relays **R31** and **R32** close their respective contacts to supply current to driving motor **34**, so that the main shaft **14** is placed in operation.

Key contacts **33** are held closed until a card has advanced sufficiently to close card lever contacts **CL2**, **CL2a** when a holding circuit will

be established from — side of line, relays R31, and R32, relay R30, its contacts R30A, stop key contacts 35, wire 37 (Fig. 3), contacts R20AL of a relay R20 (normally closed), wire 38 (Fig. 3a), pocket contacts 36 (which open if a pocket becomes full), contacts CL2a to + side of line. As long as cards continue to feed, this circuit will be maintained.

No effective circuits are completed in the first cycle and, as the first card passes brushes 17S, 17C in the second cycle, a sorting circuit will be completed to select the pocket for this card. With a 5 hole present, according to the example chosen, a circuit will be completed at the 5 time in the cycle traceable from + side of line (Fig. 3a), contacts CL1, wiper D1, 5 segment 39, wiper D2, wire 49 (Fig. 3), contact roller 16, 5 hole in the card, brush 17S, wire 41 (Fig. 3a), relay R34, sorting magnet 26, wire 42 (Fig. 3), contacts R20BL, wire 43 (Fig. 3a) to — side of line. Energization of magnet 26 at the 5 time will in the well known manner select the 5 pocket to receive this first card.

In the same manner except for difference in timing of the circuit, magnet 26 is energized in each of the succeeding cycles to select the appropriate pocket, so that the cards are distributed in the order set forth hereinabove. Brush 17C is, of course, ineffective as it rides on a blank column. If, however, such column 53 contained perforations (relating to other data), switch 44 (Fig. 3) is set in its open position for the first sorting run to interrupt any circuit through brush 17C. When the last card has passed the card levers, their contacts open and the machine stops automatically.

The cards are now replaced in the magazine, brushes 17S and 17C are shifted one column, and the start key is operated as before. Sorting under control of brush 17S takes place through the familiar circuits to distribute the cards according to their tens digital values.

The units column of the first card contains a 0 perforation and, as this passes brush 17C, a circuit is partially completed from + side of line (Fig. 3a), contacts CL1, distributor wiper D1, 0 contact segment 39, wiper D2, wire 40 (Fig. 3), contact roller 16, 0 hole in column 52, brush 17C, switch 44 (now closed), wiper 32 of timer T1, 0 segment 31, 0 wire 45 to contacts R1BL where the circuit is open. Thus, where 0 is the first digit sensed in a run, no circuit is completed. The next two cards sensed also have 0 holes in column 52 and these likewise are sorted by brush 17S.

The fourth card has a 2 hole which will complete a circuit as before to roller 16 (Fig. 3), thence through the 2 hole, brush 17C, switch 44, brush 32 of timer T1, 2 segment 31, 2 wire 45, a winding of relay R2, wire 46, resistor 47, wire 48 (Fig. 3a), reset key contacts 49, contacts 23 to — side of line. Relay R2 closes its contacts R2AL to set up a holding circuit traceable back from — side of line through wires 48, 46, contacts R2AL, second winding of relay R2, wire 50 (Fig. 3a), card lever contacts CL1 to + side of line, so that relay R2 will remain energized throughout the remainder of the run.

Relay R2 closes its contacts R2BU which concurrently complete a circuit between wire 46 and a winding of relay R1 and wire 50, so that both relays R1 and R2 are held energized.

Through similar circuits, the 3 hole in the next card will energize relay R3 which, if there had been no prior 2 or 1 hole cards, would through

its contacts R3BU energize relay R2 and the latter through its contacts R2BU would energize relay R1.

Thus, it will be noted that when any relay R2 to R9 becomes energized, it will cause energization of all lower valued relays in the chain R1 to R9. If all cards are in proper sequence, such setting of the relays is ineffective and their holding circuit will open when the cards run out and card lever contacts CL1 open. Opening of contacts 23 upon the next brush shift also breaks another point in the holding circuit.

If during this second run a card were misfiled so that a lower valued hole is sensed by brush 17C, after prior sensing of a higher valued hole, the following circuit will be completed. Assuming, specifically, that after the relays R1 and R2 have been energized a card with a 0 hole is sensed, the circuit therethrough will extend from roller 16, 0 hole, brush 17C, switch 44, wiper 32 of timer T1, 0 segment 31, 0 wire 45, contacts R1BL (now closed), wire 52, winding of relay R20, wire 48 to — side of line.

Similarly, if after relays R1 and R2 are set up a 1 hole is sensed, the circuit will run from the 1 wire 45, through contacts R1AU and R2BL to wire 52 to energize relay R20. Inspection will show that relay R20 will be energized whenever a lower value digit is sensed by brush 17C after sensing of a higher valued digit.

At this point it may be well to point out how the device makes a further check during the run to detect any erroneous double punching in the card column as where, for example, through some inadvertence an operator punches a 3 and a 1 hole in a column when only the 3 hole should appear. Inasmuch as the cards feed with the 9 hole position leading, the 3 hole would pick up relays R3, R2 and R1 and later in the same cycle the circuit through the 1 hole would pick up relay R20 in the same manner as though the 1 hole had been in a following card.

Thus, it may be stated generally that relay R20 is energized whenever a hole sensed has a lower value than a hole sensed in a prior cycle or sensed in the same cycle for the same card column. Relay R20 when energized closes its contacts R20BU to establish a holding circuit traceable in part from wire 50, the second winding of the relay, contacts R20BU to wire 48 so that it will remain energized until cards run out.

It will open its contacts R20AL (Fig. 3) in the motor relay holding circuit so that machine operation stops. It also opens its contacts R20BL in the sorting magnet circuit to prevent operation of sorting magnet 26 in cases where the value in the column being sorted is lower than the value in the column being checked and has thus not yet reached brush 17S.

To facilitate the location of a misfiled card which has already effected a pocket selection upon detection of the error, the following mechanism is provided. Timer T2 (Fig. 3) has its wiper 32 connected to brush 17S through a switch 54, so that each sorting circuit will branch from brush 17S, through switch 54, wiper 32 of timer T2, appropriate segment 31 and wire 55 to a magnet prefixed M as M9, M8, etc. to M9, thence through common wire 56 to cam contacts C1 (timed to close during the sensing of the digital positions on the card, Fig. 4), and wire 57 (Fig. 3a) to — side of line. Contacts M0A, for example, close a holding circuit from — side of line, wire 57, contacts C1, wire 56, con-

tacts M0A, winding of relay M0, wire 50, to + side of line, through card lever contacts CL1. When contacts CL1 open between card cycles, the M relay is deenergized.

If now an error occurs, resulting in energization of relay **R20** as explained, a circuit will be completed from + side of line, contacts **CL1** (Fig. 3a), wire **50** (Fig. 3), wire **60**, closed contacts **M0B** (for example), magnet **S0**, wire **61**, contacts **R20AU**, wire **57**, to - side of line. Magnet **S0** will attract its armature to raise an indicator **62** and spring urged latch **63** will snap under and hold the armature and indicator in operated position. The machine will stop upon the incidental opening of the motor circuit by which time the card in error may have been advanced to a pocket. The indicator **62** will accordingly denote the pocket containing the erroneous card and thus facilitate its location. Before operations are resumed, latch **63** is rocked manually to release the armature of magnet **S0**.

By opening switches 54 and 44 (Fig. 3), the machine may be employed for customary sorting operations without the checking features of the invention.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited 35

only as indicated by the scope of the following claim.

What is claimed is:

5 In a sorting machine having a pair of adjacent sensing elements, means for feeding a succession of record cards past said elements, whereby each card is sensed simultaneously by both sensing elements, said cards each having a pair of columns in which data are represented by designations differentially located therein, and said pair of sensing elements each traverse one of said card columns, sorting mechanism controlled by one of said elements as each card passes the said one element for sorting the cards in accordance with the location of the designation in the related column of the passing card, checking mechanism controlled solely by the other of said elements as each card passes said other element for ascertaining whether the data therein has a predetermined sequential relationship with data in the same column of a preceding card, and means controlled thereby upon detection of a variance in said relationship for preventing further operation of said sorting mechanism.
